ABSTRACT OF THE DISCLOSURE

A drag shoe for railroad cars is provided with an automatically operating throw-off device composed of two mirror inverted units each of which consists of a load-actuated lever and a throw-off lever connected thereto by means of a tension spring. The load-actuated lever comes against the force of said tension into locking engagement with a locking pawl when a wheel runs onto the drag shoe and the throw-off lever is at the same time pressed against the upper surface of the rail and thus into a position in which it is ready to throw the drag shoe off the rail as soon as the wheel has cleared the drag shoe. The units are located on both sides of the longitudinal center line of the drag shoe so that the drag shoe is always thrown to the outside of the track.

Background of the invention

This invention relates to drag shoes for railroad cars, and more specifically to a drag shoe comprising an automatically operating throw-off device which is able to throw off the drag shoe to the outside of the track when it has been cleared by a car wheel.

In the known drag shoes of this kind, additional weights are provided for the automatic throwing-off of the drag shoe. These weights come into action after relieve of the drag shoe and are intended to remove it from the rail by displacement of the center of gravity. Due to their particular construction, such devices are susceptible to trouble and, due to the unavoidable rough handling in marshalling yards, have only a short service life. They do not only require special care during handling, but they further involve the danger of accidents because neither the throwing off of the drag shoe per se nor throwing off of the drag shoe to a predetermined side of the track is ensured.

Summary of the invention

It is the object of the present invention to provide a drag shoe which avoids the use of pivotable weights, can not only reliably and efficiently be removed from the rail but can furthermore be thrown off to a predetermined side, namely the unendangered outside of the track, irrespective of which rail the drag shoe is fitted to.

To attain this object, the present invention provides a drag shoe for railroad cars which comprises a base plate formed integral with a sloping tongue at its forward end, carrying a handle with a depression at its rearward end and having an elongated cutout portion intermediate said ends; a casing-like structure having side walls and a detachable inclined wheel-engaging plate for a railroad car wheel, said casing-like structure being arranged above said elongated cutout portion in said base plate; an automatically operating throw-off device mounted in said casing-like structure and consisting of two spaced parallel throw-off units arranged on both sides of the longitudinal center line of the drag shoe and consisting each of a two-armed load-actuated lever carrying a wing-like projection extending transversely to the plane of swing of said

2

lever and outwardly of the casing-like structure through a slot in the respective side wall thereof for actuation by a car wheel flange, a double-armed throw-off lever, and a tension spring connecting one arm of the latter lever to the load-actuated lever; an angular locking pawl adapted to lock either of the load-actuated levers in its rearward position upon depression of the wing-like projection by the car wheel flange and a corresponding rearward movement of the load-actuated lever under simultaneously tensioning the tension spring and pressing the other arm of the double-armed throw-off lever against the upper surface of the rail head so as to be ready for throwing off the drag shoe to the outside of the track when said car wheel has cleared said drag shoe.

In this manner, only the throw-off lever fitted to the inner half of the rail head is actuated and laterally lifts the drag shoe and tilts it over to the outside.

Conveniently, both throw-off units are arranged side by side in mirror-inverted relationship in the casing-like structure, common axles for both load-actuated levers and for both throw-off levers being mounted in the side walls of the casing-like structure.

The angular locking pawl is preferably pivotably mounted in the depression provided in the handle and has one of its legs diverging towards its free end and provided with a hook-shaped stop for co-operation with the hook-shaped noses on the load-actuated levers, whereas the other leg is acted upon by a compression spring fitted to the handle of the drag shoe.

Further advantages of the invention reside in that the parts of the throw-off unit are removable and therefore also easily exchangeable in case of need or even completely removable so that, if desired, the drag shoe may be used without the throw-off device as a normal brake shoe.

Brief description of the drawings

FIG. 1 is a top plan view, partly in section, of a drag shoe according to the invention, the tension springs not being illustrated;

FIG. 2 is a longitudinal vertical section on the line II—II of FIG. 1, showing the drag shoe ready for action;

FIG. 3 is a similar section showing the drag shoe in locked position, ready for throwing off;

FIG. 4 is a vertical cross section on the line IV—IV in FIG. 2;

FIG. 5 is a further top plan view of the drag shoe;

FIG. 6 is a longitudinal section through the rear portion of the drag shoe in the case where the running surface of the impacting car wheel is worn-out.

Description of the preferred embodiment

In the drawings, the drag shoe is fitted to a rail head 1 (FIG. 4) and comprises a base plate 2 formed integral with a sloping tongue 3 at its forward end, a handle 4 located at the rearward end of the drag shoe and a casing-like structure consisting substantially of side walls 5 and 6 and a detachable inclined wheel-engaging plate 7 for cooperation with a railroad car wheel 8.

Two spaced throw-off units are accommodated in the casing-like structure and each of them comprises a two-armed load-actuated lever 9, a tension spring 10 and a double-armed throw-off lever 11, 12. Both the load-actuated lever 9 and the throw-off lever 11, 12 are pivotable to a limited extent round axles 13 and 14, respectively, mounted in the side walls 5 and 6 of the casing-like structure. An elongated cutout portion 15 is provided in the case plate 2 intermediate the ends thereof for the passage therethrough of the long arms 12 of the throw-off levers 11, 12.

Each two-armed load-actuated lever 9 carries a wing-like projection 16 or 17 extending transversely to the plane of swing of the load-actuated lever 9 and outwardly of

the casing-like structure through a slot 18 in the respective side wall 5 or 6 thereof. One end of the tension spring 10 is attached to the free end of the load-actuated lever 9, whereas the other end is attached to the short arm 11 of the throw-off 11, 12, the long arm 12 of which is held in its inoperative or rest position shown in FIG. 2 a short distance above the rail head 1 by means of a spring (not shown). As can be seen from FIG. 4, the parallel spaced long arms 12 of the two throw-off levers are each arranged at some distance apart from the respective lateral edge of the rail head 1.

Each load-actuated lever 9 has a bent end portion 20 provided with a hook-shaped nose 21 for cooperation with a hook-shaped stop 28 on an angular locking pawl 23, 24 pivotable round an axle 25 mounted in the carrying handle 4. A depression 27 provided in the carrying handle 4 serves for the temporary reception of the leg 24 acted upon by a compression spring 26. The other leg 23 of the locking pawl diverges towards its free end which is provided with said stop 28 cooperating with the hook-shaped nose 21 formed on the bent end portion 20 of the load-actuated lever 9.

The drag shoe operates in the following manner:

When the railroad car wheel 8 impacts against the inclined wheel-engaging plate 7 of the drag shoe, the projecting arm 16 or 17 of one of the load-actuated levers 9 is simultaneously actuated by a car wheel flange 30. The lever 9 is thereby pivoted from its inoperative position (FIG. 2) into the position shown in FIG. 3 against the force of the tension spring 10, in which position the hook-shaped nose 21 engages the stop 28 of the locking pawl 23, 24 and locks the load-actuated lever 9. Due to the wheel 8 running back after completion of the braking operation, the drag shoe will be relieved of the load and the action of the tension spring 10 thereby relaxing and suddenly displacing the throw-off 12 into the position indicated by dot and dash lines in FIGS. 3 and 6, will cause the drag shoe to be lifted on that longitudinal side of the rail head 1 which lies adjacent the wheel flange 30 in such a manner that the drag shoe will jump off the rail to the side opposite the wheel flange 30, i.e., to the outside of the track irrespective of the location of the rail to which the drag shoe is fitted.

The load-actuated lever 9 will still remain in its locked position. The release of the lever 9 required for returning it into its inoperative position will occur automatically by the drag shoe's own weight when the latter is being picked up. Such being the case, the leg 24 of the locking pawl 23, 24 which is pivotably mounted in the handle 4 is actuated against the action of the compression spring 26, and the hook-shaped nose 21 is disengaged from the stop 28.

FIG. 6 shows the loaded position with a wheel 8 having a worn-out tread 31. It can be seen that also in such a case the load-actuated lever 9 is locked by the locking pawl leg 23 by mutual engagement of the nose 21 and the stop 28, and actuation of the throw-off lever 11, 12 is ensured when the drag shoe is relieved of load.

The invention may be embodied in other specific forms without departing from the spirit or essential characteristics thereof. The present embodiment is therefore to be

considered in all respects as illustrative and not restrictive.

What is claimed is:

1. A drag shoe for railroad cars comprising
  - (a) a base plate formed integral with a sloping tongue at its forward end, carrying a handle with a depression at its rearward end and having an elongated cutout portion intermediate said ends;
  - (b) a casing-like structure having side walls and a detachable inclined wheel-engaging plate for a railroad car wheel, said casing-like structure being arranged above said elongated cutout portion in said base plate;
  - (c) an automatically operating throw-off device mounted in said casing-like structure and consisting of two spaced parallel throw-off units arranged on both sides of the longitudinal center line of the drag shoe and consisting each of
  - (d) a two-armed load-actuated lever carrying a wing-like projection extending transversely to the plane of swing of said lever and outwardly of the casing-like structure through a slot in the respective side wall thereof for actuation by a car wheel flange,
  - (e) a double-armed throw-off lever, and
  - (f) a tension spring connecting one arm of the latter lever to the load-actuated lever;
  - (g) an angular locking pawl adapted to lock either of the load-actuated levers in its rearward position upon depression of the wing-like projection by the car wheel flange and a corresponding rearward movement of the load-actuated lever under simultaneously tensioning the tension spring and pressing the other arm of the double-armed throw-off lever against the upper surface of the rail head so as to be ready for throwing off the drag shoe to the outside of the track when said car wheel has cleared said drag shoe.
2. A drag shoe as claimed in claim 1, wherein both throw-off units are arranged side by side in mirror-inverted relationship in the casing-like structure, common axles for both load-actuated levers and for both throw-off levers being mounted in the side walls of the casing-like structure.
3. A drag shoe as claimed in claim 1, wherein the angular locking pawl is pivotably mounted in the depression provided in the handle and has one of its legs diverging towards its free end and provided with a hook-shaped stop for co-operation with the hook-shaped noses on the load-actuated levers, whereas the other leg is acted upon by a compression spring fitted to the handle of the drag shoe.
